(57) **CLAIM**

We claim the ornamental design for a hot water dispenser, as shown and described.

DESCRIPTION

FIG. 1 is a front perspective view of a hot water dispenser showing our new design;

FIG. 2 is a front perspective view thereof, showing the spout in extended position;

FIG. 3 is a front perspective view of the design of FIG. 1 showing the door on the top surface in open position;

FIG. 4 is a front view thereof;

FIG. 5 is a rear view thereof;

FIG. 6 is a top plan view thereof; and,

FIG. 7 is a bottom plan view thereof.

The broken lines in the drawings are included for the purpose of illustration and form no part of the claimed design.

1 Claim, 7 Drawing Sheets
